UNITED STATES PATENT OFFICE.

BOYD SUMMERS, OF COLUMBUS, OHIO.

CENTERING-SQUARE.

1,373,367.

Specification of Letters Patent. Patented Mar. 29, 1921.

Application filed July 19, 1920. Serial No. 397,312.

To all whom it may concern:

Be it known that I, BOYD SUMMERS, a citizen of the United States of America, and resident of Columbus, in the county of 5 Franklin and State of Ohio, have invented certain new and useful Improvements in Centering-Squares, of which the following is a specification.

This invention relates to tools for determining centers and for producing a countersink at the point so determined; the said invention also contemplating the provision of novel means whereby the center or given point of a circle or square object having a 15 flat surface can be indicated and determined in inches or fractions of inches.

Furthermore, the said device is capable of use as a square or as a scale, or as a marker to draw a line with relation to some object 20 to which the device may be moved.

With the foregoing and other objects in view, the invention consists in the details of construction and in the arrangement and combination of parts to be hereinafter more 25 fully set forth and claimed.

In describing the invention in detail, reference will be had to the accompanying drawings forming part of this specification wherein like characters denote corresponding parts in the several views, and in which—

Figure 1 illustrates a top plan view of a measuring device embodying the invention;

Fig. 2 illustrates a sectional view on the 35 line 2—2 of Fig. 1;

Fig. 3 illustrates a sectional view on the line 3—3 of Fig. 1;

Fig. 4 illustrates a bottom plan view;

Fig. 5 illustrates a sectional view on the 40 line 5—5 of Fig. 1;

Fig. 6 illustrates a perspective view of one of the guides, and

Fig. 7 illustrates a perspective view of a punch and center pivot.

In these drawings, 10 denotes the blades of the implement having graduations thereon, it being shown that the blades project from the central portion 11, although preferably the blades are made integral with 50 one another and they can, therefore, be stamped from a single sheet of metal. The central portion 11 has a threaded aperture 12 which may be adjustably connected to a housing 13 which housing has an externally 55 threaded portion 14 to engage the threads of the blades. A jam or lock nut 15 also

engages the threads 14 and may serve to retain the blades in proper position to the housing.

The housing has an apertured base 16, and 60 a punch 17 projects therethrough, the said punch having an enlarged body 18 slidably in the housing terminating in a head 19 which may be struck for the purpose of operating the punch. The body 18 has a longitudinally extending groove 20 in its edge to receive a screw 21 which is threaded in the housing, and this screw serves to limit the movement of the punch which punch is held in elevated position by a spring 22 70 interposed between the bottom of the housing and the enlarged portion or body of the punch, as fully shown in Fig. 2. When the punch is to be used, it of course must have its lower or outer end resting on the work 75 to be countersunk or punched and then the head 19 is struck to produce the countersink or recess which is often used in drilling or as a mark to determine position.

Guiding members or slides are applied to 80 the blades and as the guiding member for each blade is of identical structure, a description of one of them will suffice as a disclosure of the remainder. Each guiding member comprises a block of material 23 85 having a slot 24 therein to receive a blade, the said slot being intersected by an aperture 25. The wall of the aperture 25 is threaded at the top and bottom of the guide and a set screw 26 is threaded in the top of 90 the guide to bear against a blade 10 for holding it at different positions of adjustment on the blade. This set screw is provided for positively holding the guide at different positions of adjustment, but may 95 be released to permit the guide to slide on the blade.

The guide is held in yieldable engagement with the blade by means of a friction pin 27 which is free to move in the aperture 25 of the guide, the said pin being urged against the blade by a spring 28 held in the aperture by a screw plug 29, the said plug being adjustable to increase or diminish the pressure exerted by the spring 100 and consequently, the spring regulates the frictional contact between the pin and the blade so that the guide may be free to move and yet be frictionally held in different positions of adjustment.

The guides are, of course, slidable with relation to the blades and their position can

be determined by the graduations on the blades.

One of the blades has a pointed stud or marker 30 at or near its end so that if a 5 guide is moved with relation to the end or edge of an object, the marker can be employed for making or indicating a line parallel to the edge engaged by the guide.

By adjusting the guides, the implement 10 can be used as a centering square so that the exact center of a circle or square object having a flat surface can be determined, as stated, and of course the tool is susceptible of other uses as will be appreciated by those 15 skilled in the art.

I claim:

1. In a measuring tool, a member having a central portion with a threaded aperture, blades projecting from the central portion, 20 a housing on which the central portion is threaded, a punch mounted to slide in the housing and projecting through the bottom thereof, guides slidable on the blades, each of said guides comprising a member having 25 a slot to receive a blade and an aperture ex-

tending through the body and intersecting the slot, a set screw threaded in one end of the aperture and adapted to bear on a blade, a screw plug in the opposite end of the aperture, a friction member in the said aperture bearing against a blade, and a yieldable member interposed between the plug and the friction member for urging the friction member into engagement with the blade. 30

2. In a tool of the character described, graduated blades, guides slidable on the said blades, each of the said guides comprising a member having a slot to receive a blade and an aperture extending through the body and intersecting the slot, a set 35 screw threaded in one end of the aperture and adapted to bear on a blade, a screw plug in the opposite end of the aperture, a friction member in the said aperture bearing against a blade, and a yieldable member 40 interposed between the plug and the friction member for urging the friction member into engagement with the blade. 45

BOYD SUMMERS.
